Application September 5, 1936, Serial No. 99,568

36 Claims. (Cl. 101—66)

Means have heretofore been proposed to print and issue one or more tickets by as many operations of the machine or register as there are tickets to be issued. In such machines, the main operating shaft would make as many revolutions as there are tickets to be issued. In the present invention I have provided mechanism whereby either one or two tickets may be printed and issued with only one revolution of the main operating or drive shaft. I have also provided mechanism acting in conjunction with the certifying mechanism shown in the application of William G. Orth, Serial No. 59,108, filed January 14, 1936, whereby a certifying mechanism may be rendered operative or inoperative. The present invention may be considered as an improvement on the structure shown in the said application.

I have provided interlocks to prevent the certifying shutter being raised or to prevent the movement of the duplicate ticket control lever after the machine starts operating. In other words, after the machine starts operating it is impossible to operate the certifying shutter and it is likewise impossible to move the duplicate ticket control lever from the position which it normally occupies (that is, to issue one ticket) into the position in which it would issue two tickets.

If the duplicate ticket control lever is set so as to issue two tickets and the certifying shutter is raised, the duplicate ticket control lever is automatically thrown back into the position it would occupy to issue a single ticket.

Another object of the invention is to provide mechanism whereby when the certifying shutter is lifted the duplicate ticket control lever is automatically locked in its one-ticket position.

Another object of the invention is to provide mechanism so that when the certifying shutter is in its raised position and the machine is operated one, two, or three impressions will be made on the strip to be certified and one impression will be made on the record, but no ticket will be printed or issued. In this case, I have provided mechanism to print on the record the mark "S", designating "certification". Of course, any other arbitrary sign may be employed instead of the letter "S".

Another object of the invention is to provide mechanism so that when the duplicate ticket control lever is in its one-ticket position one ticket will be printed and issued and one impression will be made on the record strip but the certification mechanism is rendered inoperative.

Another object of the invention is to provide

mechanism so that when the duplicate ticket control lever is in its two-ticket position the machine will print and issue two tickets with the character "DU", designating "duplicate" on the first ticket and the same variable data will be printed on the second ticket except that the "DU" designating "duplicate" will not appear on the second ticket and in this case the certification mechanism will be rendered inoperative. When the duplicate ticket control lever is in its two-ticket position only one impression will be made on the record, which record will contain the character "DU". In other words, when the machine is operated with the duplicate ticket control lever in its two-ticket position the variable data, including "DU", will be printed on the first ticket and on the record, after which the character "DU" will be moved out of printing alignment and the second ticket will then be printed, but there is no impression on the record during the printing of the second ticket.

Another object of the invention is to provide mechanism so that when the duplicate ticket control lever is in its two-ticket position and the machine is operated the duplicate ticket control lever will be automatically returned to its one-ticket position before the second ticket has been printed.

Another object of the invention is to provide mechanism so that when the certification slip is inserted the certifying shutter is locked against being depressed against the inserted slip to prevent the certification slip being torn. In structures heretofore provided considerable trouble has been experienced because of the fact that the shutter would tear the inserted slip. I have provided locking mechanism to eliminate the above objection.

Other objects and advantages of the invention will appear in the detail specification and claims which follow.

Referring to the drawings:

Fig. 1 is a side elevational view, a part of the casing being broken away, of the machine taken from the operating side. By operating side, I mean the side or end of the register at which the power is applied to operate the machine.

Fig. 2 is a detail perspective view of the duplicate ticket control lever taken from the opposite side from that shown in Fig. 1.

Fig. 3 is an elevational view, partly in cross section, taken on the line 3—3 of Fig. 6.

Fig. 4 is a detail elevational view of the holding mechanism for the duplicate ticket control lever shown in the upper left hand part of Fig. 1.

50

55

Fig. 5 is a plan view of one of the tickets issued, it being the first ticket issued on a duplicate ticket issuing operation.

Fig. 6 is a front elevational view of the certifying shutter and connected mechanism.

Fig. 7 is a cross sectional view taken on the line 7—7 of Fig. 6 and looking towards the left.

Fig. 8 is a detailed view of the certifying shutter locking mechanism shown in the lower left-hand part of Fig. 6, and

Fig. 9 is a detail of the electroplate and feed roll operating mechanism as shown on the right-hand side of Fig. 1.

In all of the said views the casing of the register has been eliminated for the sake of clearness, it of course being understood that a suitable casing is provided.

Referring to the drawings, side walls 1, 2, 3, and 4 are provided, all of which are supported by a base plate 5. Ordinarily the machine will be driven by a motor but it may be operated by a hand crank and for simplicity I have shown a crank 6 provided with an operating handle 7. The crank 6 is secured to a shaft 8 on which is secured a pinion 9 and a gear 10, the pinion 9 having one-half as many teeth as the gear 10. The gear 10 meshes with and drives a gear 11 secured to a shaft 12, the said gears 10 and 11 having the same number of teeth. Secured to the shaft 12 is a Geneva gear 13, as shown in Patent 1,966,078, which operates a Geneva pinion 14 as shown in the said patent, the gear 13 being out of line with the pinion 9 so that it does not mesh therewith. The pinion 14 is mounted on a stud 15 carried by the side wall 1. The pinion 14 meshes with and drives a pinion 17 rotatably mounted on a shaft 18 on which is mounted an electroplate 19. Fixed to the shaft 18 is a disk 20 having a radial slot 21. Secured to the disk 20 and the shaft 18 is a pinion 23 having the same number of teeth as the pinion 17. When the pinion 22, as shown in Fig. 1, is brought into mesh with the loose pinion 17 and the pinion 23 which is secured to the shaft 18, the rotation of the pinion 17 will be communicated to the pinion 23 through the broad pinion 22 which meshes with both of the said pinions and the shaft 18 and electroplate 19 will thereby be rotated. Secured to the shaft 18 is a pinion 24 which meshes with and drives a pinion 25 fixed on the shaft 26, to which shaft the feed roller 16 is secured.

The gearing is such that when the handle 7 is rotated two complete revolutions the Geneva gear 13 will be rotated twice. If the broad pinion 22 is in mesh with the pinions 17 and 23 the electroplate and feed roller will be rotated twice. As will be hereinafter described, the pinion 22 is brought into mesh with the pinion 17 and the fast pinion 23 as soon as the machine starts operating if two tickets are to be issued so that the electroplate and feed roller will be given two revolutions. If only one ticket is to be issued, however, I will describe mechanism whereby the broad pinion 22 occupies the position shown in Fig. 1 until after the first revolution of the gear 13, at which time the broad pinion 22 will be engaged with the loose pinion 17 and the fast pinion 23 so that the electroplate and feed roller will be operated once. I will also describe mechanism whereby when the certifying shutter is raised the pinion 22 will not be engaged with the loose pinion 17 and fast pinion 23 and, therefore, the electroplate and feed roller will not be operated at all, so that no ticket will be issued.

The pinion 9 meshes with and drives a gear 27,

having twice as many teeth as the pinion 9, which pinion 27 is fast to the main drive shaft 28, to which is also secured a disk 29 having a radial slot 30 and a pinion 31 having one-half as many teeth as the gear 27. The pinion 31 meshes with and drives a pinion 32 having a pin 33 secured thereto, the gearing being such that the pinion 32 is given one revolution for each two revolutions of the crank 6. The gear 27 meshes with and drives a pinion 34 which meshes with and drives a gear 35, the gearing being such that the gear 35 is given one revolution for each two revolutions of the crank 6. The gear 35 is secured to a shaft 36, to which is secured a cam disk 37 of the shape shown in dotted lines in Fig. 1; that is, it has an outer arcuate surface 38, an abrupt wall 39 extending substantially radially, a cam surface 40, an arcuate surface 41 having a less radius than the arcuate surface 38, and a cam surface 42.

The direction of rotation of the main gears and pinions mentioned above is as follows: The crank 6, pinion 9, and gear 10 are rotated clockwise, causing an anti-clockwise rotation of the pinion 31, pinion 27, gear 11, and Geneva gear 13, causing a clockwise rotation of the pinion 34 and pinion 14, causing an anti-clockwise rotation of gear 35 and pinion 17. It also appears that when the crank 6 is given two rotations the main drive shaft 28 is rotated only once, the pinion 32 is rotated once, the pinion 17 is rotated twice, and the gear 35 is rotated only once.

As heretofore mentioned, when the crank 6 is rotated clockwise two revolutions the gear 10 will rotate the shaft 12 and the gear 13 through 35 two revolutions in an anti-clockwise direction. Secured to the shaft 12 and gear 11 is a disk 43 which carries a wrist pin 44 on which wrist pin is mounted a pitman 45 which at its other end is secured to a pin 46 mounted in an oscillating printing carrier 47. As shown in Patent 1,858,813 there are two side plates to the oscillating printing carrier, both of which are mounted on a support 48. Both of these plates are provided with slots 49 and 50 which receive shafts 51 and 52 respectively on which are mounted platens 53 and 54 respectively. Trained over the platen 54 is a strip of ticket paper 55 which passes from a ticket supply roll not shown over the platen 54 and thence between the electroplate 19 and feed roller 16 so that the platen 54 can be considered as the ticket platen. A strip of record paper 56 passes from a supply roller over the platen 53 to a record take up roller as shown in Patent 1,858,813. An ink roller 57 is mounted on a shaft 58 carried by the side walls of the oscillating printing carrier. Mounted on the shaft 59, above the printing carrier 47, are a plurality of type wheels 61, each of which is provided with an actuating pinion 60, as shown in Figs. 1 and 6. The parts are normally in the position shown in Fig. 1. When the crank 6 is rotated in a clockwise direction two revolutions the disk 43 will rotate anti-clockwise two revolutions so as to bring the ink roller 57 into engagement with the type wheels 61 and if the shaft 52 is in the upper part of the slot 50 the platen 54 will make a printed impression on the ticket strip and thereafter the type wheels will be again inked. But the ink roller and the record strip will be brought into engagement with the type wheels provided the shaft 51 is at the upper end of the slot 49 and this would be repeated a second time upon the second revolution of the disk 43 if the said shafts remained at the upper end of the slots. On a certifying operation,

I have provided mechanism hereinafter to be described so that the record platen causes an impression to be made only once while the ticket platen remains in its lower position and makes no printed impression during the entire time that the disk 43 makes its two revolutions.

A duplicate control lever 62, shown in Figs. 1, 2, 3, and 4, is pivoted on a shaft 63. This lever 62 is bent outwardly and then inwardly forming an elbow 64 which receives a fixed plate 65. The lever 62 carries a pin 66 on which is pivoted a lever 67 having an inwardly extending release arm 68. The downward movement of this release arm is limited by an underlying flange 69 carried by the lever 62. Pivoted to the frame of the machine on a pin 70 is a lever 71 having an upstanding arm 72 provided with a shoulder 73. The lever 71 is also provided with an arm 74 terminating in a surface 75 below a pin 76 carried by an arm 77, which arm is pivoted on the shaft 63 and at its upper end is provided with an over-turned flange 78 secured to an arm 79, which as shown in Fig. 6 is bent downwardly and is secured to a segmental gear 80 which meshes with and seats one of the pinions 60 integral with one of the type wheels 61 on which is a printing character 61', being as shown simply the letter "S" signifying "certification". The parts are so constructed that when we are certifying the letter "S" will be in printing position to print on the record strip. It would, of course, also print on the ticket except that no ticket is printed when we are certifying.

A lever 81 is pivoted on a stud 82. This lever is normally urged counter-clockwise by means of a spring 83. The lower end of the lever is normally seated in the notch between the abrupt wall 39 and the cam surface 40 of the disk 37. This lever 81 carries pins 84 and 85 and at its extreme upper end is provided with a presser foot 86. The pin 85 overlies the arm 74. The pin 84 normally rests on a cam surface 87 of a lever 88 pivoted on a stud 89. At the other end of the lever 87 is a locking shoulder 90 which under certain conditions engages the over-turned flange 91 of the lever 62. The lever 62 is in its down position as shown in Fig. 1 when one ticket is to be issued or when certifying is being done, but when we wish to issue two tickets we raise the lever 62 so that the part 64 thereof engages the shoulder 73 of the arm 72, thereby holding the lever 62 in its raised or two-ticket position. If the machine is operated when the lever 62 is in its two-ticket position the pin 85 on the lever 81 will engage the cam surface 92 on the arm 74 when the cam surface 42 of the disk 37 reaches the lower end of the lever 81, thereby shifting the arms 74 and 72 in a clockwise direction so as to disengage the shoulder 73 from the lever 62, in which case the lever 62 is dropped or returned to the position shown in Fig. 1 by means of the spring 93. If the lever 62 is in its one-ticket position as shown in Fig. 1 and the machine is operated, the cam surface 40 will move the lever 81 to a slight extent in a clockwise direction, removing the pin 84 from the cam surface 87 of the lever 88 and the spring 94 connected to a downward extension 95 of the lever 88 so as to bring the shoulder 90 into engagement with the flange 91 on the lever 62. It, therefore, appears that as soon as the machine starts operating it would be impossible to move the lever 62 from its one-ticket position as shown in Fig. 1 into its upper or two-ticket position.

The lever 62 is provided with an upstanding substantially arcuate arm 96 so as to conform

with the general contour of the casing of the machine, which arm carries a pin 97 which engages a slot 98 in a link 99, which link at its other end carries a pin 100 which connects the said link to a lever 101, which lever is pivoted on a pin 102. 5

A spring 101' urges the lever 101 counter-clockwise. The said lever 101 is provided with an L-shaped slot 103 which receives a pin 104 carried by a lever 105 pivoted on a stud 106. The lever 105 has a downwardly extending arm 107 terminating in a projection 108 which normally lies in the radially extending slot 21, thereby normally locking the shaft 18 against rotation so that no ticket could be issued. Under such conditions the pin 104 lies at the lower end of the L-shaped slot 15 103. The lever 105 is also provided with an arm 109 which carries a stud 110 on which the wide pinion 22 is mounted. I have provided an aligning pawl 111 to maintain the pinion 22 in proper position so that its teeth will be readily received by the pinions 17 and 23. It is obvious from inspecting Fig. 1 that as long as the projection 108 is holding the disk 20 and shaft 18 from rotation the pinion 22 cannot be brought into mesh with the pinions 17 and 23. However, if the duplicate control lever 62 were raised to its two-ticket position its pin 97 would move the link 99 to the left as viewed in Fig. 3, or to the right as viewed in Fig. 1, and the lower portion of the L-shaped slot 103 would shift the projection 108 out of engagement with the radial slot 21 and would bring the broad pinion 22 into mesh with the pinions 17 and 23 so that if the machine were now operated the electroplate and feed roller would be rotated twice, thereby issuing two tickets. 35

A lever 112 is pivoted on the pin 102 and is provided with an arm 113 to which is attached a spring 114. This lever 112 is provided with an upstanding wall 115, a cam surface 116, and a slot 117. When we are not certifying the flange 78 connected to the certifying or non-certifying arm 79 overlies the portion of the lever 112 between the wall 115 and the cam surface 116. When we move the parts so as to certify, the flange 78 is moved to the left as viewed in Fig. 1 so that the flange 78 will be a little to the left of the cam surface 116 and the lever 112 will be moved upwardly by the spring 114. If the parts are again moved from the certifying to the non-certifying position, the flange 78 moves to the right as viewed in Fig. 1 engaging the cam surface 116 and rotating the lever 112 in a counter-clockwise direction, thereby moving the slot 117 downwardly. Extending within the slot 117 is a pin 118 carried by a lever 119, which lever is pivoted on a pin 120 carried by the lever 101. This lever 119 is provided with a downwardly extending shoulder 121 and an upwardly extending projection 122. When the duplicate control lever 62 is in its lower position and, therefore, in position to issue one ticket the projection 122 lies below and slightly to the left as viewed in Fig. 1 of a fixed pin 123. If now the machine is operated the cam surface 40 moves the presser foot 86 of the lever 81 almost into contact with the shoulder 121 of the lever 119, the broad pinion 22 being out of engagement with the pinions 17 and 23. However, when the shaft 36 has been rotated so as to bring the cam surface 42 into engagement with the lower end of the lever 81, 70 the lever 81 is rotated clockwise so that the presser foot 86 engages the shoulder 121 of the lever 119, thereby rotating the lever 109 clockwise as viewed in Fig. 1 and moving the broad pinion 22 into engagement with the pinions 17 and 23 75

while disengaging the projection 108 from the radial slot 21. This occurs at approximately the time that the crank 6 has completed its first rotation so that during the first rotation of the crank 5 6 the shafts 18 and 26 have not been rotated and no ticket has been issued, but during the second rotation of the crank 6 the shafts 18 and 26 are given one complete revolution so as to issue a ticket. As heretofore mentioned, when the lever 10 10 62 is elevated to its two-ticket position the broad pinion 22 will be moved into mesh with the pinions 17 and 23 so that the shafts 18 and 26 will be given two revolutions when the machine is operated. When the lever 62 is in its upper or 15 15 two-ticket position and the lever 101 has, therefore, been rotated clockwise as viewed in Fig. 1 by the movement of the lever 62 to its two-ticket position, the lever 119 is moved to the right as viewed in Fig. 1 so that the projection 122 lies beneath the fixed pin 123. But the lever 112 has not 20 20 been disturbed by this movement by reason of the pin and slot connection between the levers 112 and 119.

As will hereinafter be described, if the certifying 25 25 shutter has been raised so as to permit the insertion of a certifying slip, the flange 78 will have moved to the left as viewed in Fig. 1 over the cam surface 116 so that the spring 114 will rotate the lever 112 in a clockwise direction and through the 30 30 pin and slot connection 117 and 118 the lever 119 will be raised so that the projection 122 will lie to the left of the fixed pin 123, thereby preventing the movement of the projection 122 to the right as viewed in Fig. 1 and thereby locking the lever 62 35 35 in its lower or one-ticket position.

Referring to Figs. 6, 7, and 8, the mechanism which I have provided is an improvement on that shown in application Serial No. 59,108, hereinbefore mentioned. In that application there was 40 40 shown a table 4 on which a certifying slip might be placed and there was also shown printing mechanism for the strip to be certified whereby one or a plurality of printed impressions might be made on the printed slip. In the said application 45 45 there was a handle 20 whereby a shutter might be raised so as to permit the insertion of the slip. Instead of this mechanism I have provided a lifting handle 124 projecting through the casing of the machine, which lever is pivoted on a shaft 50 50 125. When this lever is in its down position the certifying shutter does not permit of the insertion of a slip, but when the lever 124 is raised it does permit the insertion of a slip. The lifting handle 124 is normally in the position shown in Fig. 7 55 55 but when lifted it engages a pin 126 to which is secured a spring 127. The pin 126 is carried by a lever 128 provided with an L-shaped cam slot 129. The lever 128 is pivoted on the shaft 125. Received within the slot 129 is a roller 130 carried 60 60 by a pin 131 carried by a lever 132, which lever 132 is secured to a shaft 133. The shaft 133 is the shaft to operate the clutch mechanism shown for the certifying printing mechanism in the said application 59,108, which forms no part 65 65 of the present invention. The lever 132 carries a pin 134 to which is attached a link 135 which is pivoted at its other end to a stud 136, which stud is carried by a crank arm 137 secured to the shaft 125 so that when the lifting handle 124 is 70 70 lifted the lever 128 is rotated clockwise as viewed in Fig. 7 and the cam slot 129 moves the lever 132 in a counter-clockwise direction as viewed in Fig. 7, thereby moving the link 135 to the left as viewed in said figure and rotating the crank arm 137 and the shaft 125 to which it is fixed in a 75 75

clockwise direction. The reason that the lever 128 is not directly connected to the shaft 125 is because the movement of the lever 128 would rotate the shaft 125 too much and I have, therefore, employed the link mechanism 135 and crank 5 arm 137, the pin 134 being so positioned as to rotate the shaft 125 the proper amount. When the lifting handle 124 is lifted the shaft 125 is rotated clockwise.

Carried by the lever 128 is a pin 138 which is 10 received within a slot 139 in an arm 140 carried by the shutter 141 so that when the said lifting handle 124 is raised and shutter 141 is raised and when the lifting handle 124 is in its lower position as shown in Fig. 7 the shutter 141 is in its 15 lower position so as to cover the slip receiving slot and thereby prevent the insertion of a slip to be certified. When the handle 124 is raised the shutter 141 is raised from the position shown in Fig. 6 to a position slightly above that shown 20 in Fig. 8, so that the certifying strip 142 can be inserted beneath the shutter 141 and above the table 143. The shutter 141 is provided with guide slots 144 which receive guide screws 145. It is also provided with an outstanding lug 146 and a 25 pin 147 which is received within a slot 148 in a link 149. The link 149 is pivoted to a lever 150 by means of a pin 151. The lever 150 is pivoted on a stud 150' and has an upper surface 152 and a slip contacting arm 153. When the shutter is 30 30 in its down position as shown in Fig. 6 it is, of course, impossible to insert the slip 142 for its entrance is prohibited by the slip contacting arm 153 and also by the shutter 141. When, however, the lifting handle 124 is raised the pin 147 travels 35 35 to the upper end of the slot 148 and pulls upwardly on the pin 151, thereby depressing the slip contacting arm 153 so that now the slip 142 may be inserted. When the operator drops the arm 124 the shutter 141 moves downwardly contacting 40 40 the slip 142 which presses downwardly on the slip contacting arm 153 moving the lever 150 in a counter-clockwise direction as viewed in Figs. 6 and 8 so as to bring the upper surface 152 of the lever 150 beneath the lug 146, thereby stopping 45 45 the downward movement of the shutter 141 and preventing the said shutter from continuing its downward movement and possibly tearing or damaging the inserted slip. A spring 154 normally holds the lever 150 in the position shown 50 50 in Fig. 6 and tends to rotate the same in a clockwise direction, but its pressure is so small as to eliminate any hazard of the inserted slip being damaged. When the inserted slip is removed the spring 154, however, would move the lever 150 so 55 55 as to disengage its upper surface 152 from the lug 146 and the shutter would again fall and the slip contacting arm 153 would again resume the position shown in Fig. 6.

As before mentioned, when the lifting handle 60 60 124 is raised the shaft 125 is rotated for a given distance in a clockwise direction. This shaft 125 passes through the walls 1 and 2 and on the right-hand side of the side wall 1 as viewed in Fig. 6 it carries a crank arm 155 (Figs. 6 and 1). 65 65 As viewed in Fig. 1 when the shutter is being raised the crank arm 155 is being rotated in a clockwise direction so that the pin 156 carried by the crank arm 155 is lowered. The pin 156 is in its upper position when the shutter is down 70 70 and is in its down position when the shutter is up. When the shutter is being raised and the pin 156 is being moved downwardly it pulls downwardly the link 157 pivoted on the said pin 156. The upper end of the link 157 is provided with 75 75

a pin 158 secured to the lever 77, which, it will be remembered, controls the certifying character "S" on the type wheel 61. The net result is that when the shutter is in its raised position, 5 the character "S" is in printing position, but when the shutter is down so as not to be certifying the character "S" is in non-printing position.

If the lever 62 were in its two-ticket position or in its raised position and we now elevated the 10 shutter so that we could certify, the downward movement of the link 157 would rotate the arm 77 in a counter-clockwise direction so that its pin 76 would engage the surface 75 of the arm 74, thereby rotating the shoulder 73 out of engagement 15 with the lever 62 and the spring 93 would cause the said lever 62 to be dropped to its single ticket position, which is the position it normally occupies.

The pin 156 also supports a link 159 which at 20 its lower end is provided with a pin 160, which pin is also carried by a lever 161 pivoted on a stud 162. The lever 161 carries an outstanding lug 163 which extends through the slot 164 in the plate 1 of the machine. When the shutter is in 25 its upper position adapted to receive an inserted slip the lug 163 is at the bottom of the said slot 164 or in the position in which no ticket should be issued. When the shutter is down so that a slip cannot be certified the lug 163 is at the upper 30 end of the slot 164 so that a ticket will be issued.

Pivoted on the support 48 of the oscillating printing carrier is a lever 165 having a cam surface 166 and a depending control arm 167. When the oscillating printing carrier is oscillated 35 and the lug 163 is at the bottom of the slot 164, that is, in position in which certifying will be done, the control arm 167 passes above the lug 163 and the shaft 52 lies at the bottom of the slot 50 so that the platen 54 will be in its lower 40 position and would, therefore, not bring the ticket paper into engagement with the printing characters so that no ticket whatsoever is printed when the certifying shutter is raised. When the certifying shutter, however, is down and the lug 45 163 is at the upper end of the slot 164 as viewed in Fig. 3, and if the machine is now operated so as to oscillate the printing carrier, the spring 168 secured to the lever 165 and the printing carrier will hold the lever 165 in engagement with the stop pin 169 and the lever 165 will move with 50 the printing carrier until the control arm 167 engages the lug 163 and upon the continued motion of the printing carrier the cam surface 166 will raise the ticket platen so that its shaft will be at the upper end of the slot 50 and in a position to 55 cause printing to be done on the ticket strip. If the lever 62 is in its one-ticket position the oscillating carrier would still make two back and forth motions, but as heretofore described the ticket would not be fed. However, the ticket strip would be on both cycles of the printing carrier brought into engagement with the printing type so that we would have two printed impressions on the ticket but as there has been no 60 movement of the ticket because the feeding mechanism of the electroplate and feed rollers is inoperative, the two impressions would be on the same line and there is no disadvantage in having the two impressions made on the ticket for when the ticket was finally issued we would see only one impression, the two impressions coinciding. If, however, we are to issue two tickets, by moving the lever 62 to its upper position the ticket paper 65 would be fed as heretofore described between the two impressions and we would have two tickets.

It is desirable to always print on the record, however, one time regardless of whether one ticket is issued or two tickets are issued or the certifying mechanism is operated. It will be remembered that the pinion 32 rotates clockwise 5 one revolution for a complete operation of the machine, that is, for each two revolutions of the crank 6, and that this pinion 32 carries a pin 33 which is normally in the position shown in Fig. 1. Regardless of whether the lever 62 is in its one- 10 or two-ticket position and regardless of whether the certifying shutter is in its up or down position, the pin 33 will contact the lower end of a lever 170 pivoted on the support 48, which lever at its upper end carries a cam surface 171. When 15 the pin 33 strikes the lever 170 it will rotate the said lever in a counter-clockwise direction as viewed in Fig. 1 so that the cam surface 171 will elevate the record platen so as to cause one 20 printed impression to be made on the record paper when the printing carrier is oscillated, but since the pinion 32 makes only one revolution this printed impression is made only once on the record. The pin 33 is so positioned that the 25 printed impression will be made on the record on the first cycle of the printing carrier regardless of the position of the lever 62 or of the certifying shutter.

Secured to the arm 96 of the lever 62 is an arm 172 which is secured to an arcuate rack 173 which 30 meshes with and drives a pinion 174 connected to a type wheel 175 on which appears the character "DU" representing "duplicate". When the lever 62 is in its two-ticket position the printing character "DU" will be in printing position and in 35 alignment with the other type wheels but when the lever 62 is in its one-ticket position the printing character "DU" will be out of printing position. It will be remembered that if the lever 62 is moved to its two-ticket position and the machine is operated, the character "DU" will be in 40 printing position and will, therefore, print on both the ticket and the record but that when the first ticket has been printed the pin 85 will engage the cam surface 92 and move the shoulder 73 out of holding engagement with the lever 62 so that the said lever 62 will be dropped, thereby moving the printing character "DU" out of printing alignment. The net result is that when the lever 62 is moved to its two-ticket position the character "DU" is printed on the first ticket and on 45 the record but is not printed on the second ticket and there is no impression made on the record during the second operation.

By the above structure I have provided means 50 to accomplish all of the aforesaid objects.

When the shutter is raised so as to receive an inserted slip it is impossible to raise the lever 62 because the projection 122 engages the fixed pin 123. However, the shutter can be raised 60 when the lever 62 is in its two-ticket position, but this releases the lever 62 and it is returned to its one-ticket position.

Secured to the arm 77 is a plate 176 provided with two V-shaped notches 177. A slide bar 178 is provided at its upper end with a nose 179 adapted to be seated in either of the said notches. The slide bar is provided with conventional pin and slot connections so that it can move only 65 upwardly or downwardly but a spring 180 tends 70 to pull the slide bar upwardly so as to seat its nose in one or the other of said notches. The lower end of the slide bar is provided with a prong 181 adapted to be seated within the radial slot 30 of the disk 29 when the said slide bar 75

is in its lower position. The object of this structure is to lock the machine against operation unless the certification shutter has been completely raised or completely lowered, thereby shifting the plate 176 so that the nose 179 can be seated in one or the other of its notches. The prong 181 rests immediately above the periphery of the disk 29 when the machine is being operated. This prevents the depression of the slide bar 178 and, therefore, prevents operation of the certification shutter while the machine is being operated. In other words, the operator must either raise or lower the certification shutter or have the same positioned in one or the other of its two positions in order to operate the machine at all and he cannot change the position of the shutter after the machine has started operation.

I have provided a pin 182 in a slot in the said slide bar 178, which pin controls the locking mechanism for all of the type wheels, as fully shown and described in Patent 1,858,813.

In the operation of the register one complete operation of the operating device, including two rotations of the crank 6 and one rotation of the main shaft 28, will impart two movements to the platen carrier 47 and one or two tickets will be printed and issued according to the position of the control lever 62, provided the shutter is in its closed position. When the control lever 62 is in its lower or one ticket position, with the parts in the positions shown in Fig. 1, the two rotations of the crank 6 will cause the gear 35 and cam 37 to make one complete rotation. During the first part of this rotation the cam will impart initial movement to the lever 81, thereby moving the pin 84 out of engagement with the cam surface on the locking lever 88 and permitting that lever to be moved by the spring 94 into locking engagement with the flange 91 on the control lever, thereby locking the latter in its lower position. During this initial movement of the cam the printing mechanism will be operated to make an impression on both the ticket strip and the record strip. Upon the continued rotation of the cam the cam surface 42 will impart further movement to the lever 81 causing the nose 86 thereof to engage the shoulder 121 on the lever 119, thereby causing that lever to rock the lever 101 about its axis so that the pin 104, which lies in the vertical portion of the slot 103, will be actuated to swing the lever 105 about its axis and thus move the broad pinion 22 into mesh with the pinions 17 and 23, thereby connecting the ticket feeding mechanism with the operating mechanism. The arcuate portion 38 of the cam will retain the pinion in operative position until the cam has completed its rotation, thus causing the ticket material to be fed from the machine. Just before the cam completes its movement the shoulder 39 thereof will move past the end of the lever 81 and the latter will be returned to its normal position by the spring 83, the pin 84 striking the cam surface on the locking lever 88 and returning the same to its unlocking position. The printing mechanism will operate a second time just before the feeding movement of the ticket strip begins but inasmuch as the feeding mechanism has not operated the impression thus made will be superposed on the impression made by the first operation of the printing mechanism and the ticket and record strip will each carry a single impression.

When the control lever is moved to its upper or two ticket position the link 99 (Fig. 3) will

rock the levers 101 and 105 to move the pinion 22 into operative engagement with the pinions 17 and 23 so that the feeding rollers will make two rotations, with a dwell between rotations, for each rotation of the operating shaft 28 and cam 37 and the printing mechanism will operate prior to each feeding movement of the rollers to print an impression on each ticket issued, but a single impression only will be printed on the record strip, due to the control of the platen 10 53 by lever 170. When the control lever is moved to its upper position it is automatically locked in that position by the locking lever 71 and when the cam surface 42 of the cam 37 engages the lever 81 the pin 85 will be caused to engage the cam surface 92 of the locking lever 71 and rock the latter to release the control lever for movement to its lower position by the spring 93. However, the nose 86 of the lever 81 will have been moved into engagement with or close to, the shoulder 20 121 on the lever 119 and will be held in that position by the arcuate surface 38 of the cam until the cam has practically completed its rotation, thus retaining the pinion 22 in its operative position. The pin and slot connection, 97—98, between the arm 96 of the control lever and the link 99 permits the control lever to have reverse movement without imparting movement to the lever 101. When the shoulder 39 of the cam 37 clears the lever 81 the latter will be retracted 30 and the spring 101' will actuate the lever 101 to move the pinion 22 to its inoperative position.

When the shutter is elevated to permit the insertion of a slip to be certified the lever 77 will be moved to the left, in Fig. 1, to carry the flange 18 thereof beyond the cam surface 116 of the lever 112, and the spring 114 will actuate that lever and the lever 119 to move the projection 122 of the lever 119 into line with the fixed pin 123, and to move the shoulder 121 out of line with the lever 81, thereby locking the lever 101 and consequently the control lever against movement and retaining the pinion 22 in its inoperative position, so long as the shutter is raised. When the shutter is lowered the lever 77 will be moved in the other direction to cause the flange 18 thereof to act on the cam surface 116 of the lever 112 and thus move the projection 122 out of line with the pin 123. If the shutter should be raised while the control lever is in its upper position the first mentioned movement of the lever 77 will cause the pin 76 to actuate the locking lever 71 and thus release the control lever for movement to its lower position by its spring 93.

I realize that many changes may be made in the specific form of the invention as shown herein, which form I have used by way of illustration, and not by way of limitation. I, therefore, desire to claim the invention broadly, reserving to myself the right to make all changes which may fairly fall within the scope of the spirit of the invention, except as I may limit myself in the annexed claims.

Having now described my invention, I claim: 65
 1. In a register, a main shaft, a ticket and record printing mechanism including a character which may be shifted into or out of printing position, control means whereby two tickets will be printed while only one impression is made 70 on the record, the first ticket and the record including the impression from the said character, and means whereby the character is then shifted so that the second ticket will not receive the impression from the character. 75

2. In a register, a printing mechanism, means whereby the said mechanism may be caused to print either one or two tickets while making only one impression on a record, a character forming a part of the said mechanism and adapted, when two tickets are being issued, to print on the first ticket and the record, and means to shift said character prior to printing the second ticket into inoperative position. 5
- 10 3. In a register having mechanism for printing on a ticket strip, mechanism for advancing said strip to issue a printed ticket, and an operating device, means actuated by said operating device to cause said printing mechanism to make two printing operations on each complete operation of said operating device, means actuated by said operating device to operate the mechanism for advancing said ticket strip, and a controlling device to cause the last mentioned means to advance said ticket strip after each printing operation or to advance the same after one only of said printing operations. 10
- 15 4. In a register having mechanism for printing on a ticket strip, mechanism for advancing said ticket strip to issue a printed ticket, mechanism for printing on a record strip, and an operating device, means actuated by said operating device to cause said printing mechanism to make two printing operations upon each complete operation of said operating device, means actuated by said operating device to operate the mechanism for advancing said ticket strip, a controlling device to cause the last mentioned means to advance said ticket strip after each printing operation or to advance the same after one of said printing operations only, and means controlled by said operating device to operate said record printing mechanism once upon each complete operation of said printing device. 15
- 20 5. In a register, a group of type wheels, printing mechanism having means for taking an impression from said type wheels on a ticket strip and having other means for taking an impression from said type wheels on a record strip, an operating device, means for imparting two operative movements to said printing mechanism and causing two impressions to be taken on said ticket strip upon each complete operation of said operating device, means actuated by said operating device for advancing said ticket strip, a device for controlling said advancing means to cause said ticket strip to be advanced after each printing operation and thus space said impressions one from the other or to cause said ticket strip to be advanced after the second printing operation only and thus superpose said impressions one on the other, and means for rendering the means for taking said impression on said record strip inoperative during the second movement of said printing mechanism. 20
- 25 6. In a register having mechanism for printing on a ticket strip, mechanism for feeding said ticket strip to and beyond said printing mechanism, and a device to operate said printing mechanism, normally inoperative means for connecting said operating device with said strip feeding mechanism, and means controlled by said operating device to render said connecting means operative after a predetermined movement of said operating device. 25
- 30 7. In a register having ticket printing mechanism, ticket issuing mechanism, and a device to operate said printing mechanism, normally inoperative means for connecting said ticket issuing mechanism with said ticket printing mechanism, and means controlled by said ticket issuing mechanism to render said connecting means operative after a predetermined movement of said ticket issuing mechanism. 30
- 35 8. In a register having ticket printing mechanism, ticket issuing mechanism, and an operating device, means actuated by said operating device to impart two printing movements to said printing mechanism upon each complete operation of said operating device, a normally inoperative connection between said operating device and said ticket issuing mechanism, means controlled by said operating device to render said connection operative after the second printing movement of said printing mechanism, and manually operable means for rendering said connection operative independently of said operating device. 35
- 40 9. In a register having ticket printing mechanism, ticket issuing mechanism, and an operating device, means actuated by said operating device to impart two printing movements to said printing mechanism upon each complete operation of said operating device, a normally inoperative connection between said operating device and said ticket issuing mechanism, a manually operable device to render said connection operative, means controlled by the initial movement of said operating device to lock said manually operable device against movement, and means controlled by said operating device to render said connection operative to issue a ticket after the second printing movement of said printing mechanism. 40
- 45 10. In a register having ticket printing and issuing mechanism, and a device for operating said mechanism, controlling means including a movable member to cause said mechanism to print and issue one ticket when said movable member is in one position and to print and issue two tickets when said movable member is in another position, and means controlled by said operating device to move said movable member from its two ticket position to its one ticket position. 45
- 50 11. In a register having ticket printing and issuing mechanism, and a device for operating said mechanism, controlling means including a movable member to cause said mechanism to print and issue one ticket when said movable member is in one position and to print and issue two tickets when said movable member is in another position, and means for moving said movable member from its two ticket position to its one ticket position after the first ticket has been printed and prior to the issuance of the second ticket. 50
- 55 12. In a register, ticket printing mechanism, an operating device for said mechanism, ticket issuing mechanism, means for operatively connecting said operating device with said ticket issuing mechanism, a controlling member, means controlled by said controlling member to render said connecting means inoperative when said member is in its normal position and to render said connecting means operative when said member is moved from its normal position, and means controlled by said operating device to return said controlling member to its normal position prior to the completion of the ticket issuing operation while maintaining said connecting means operative. 55
- 60 13. In a register having ticket printing mechanism, ticket issuing mechanism, and means for 60
- 65 70 75

- operating said mechanisms, a controlling member, means controlled by said member for rendering said issuing mechanism operative or inoperative, said register being adapted to receive a slip to be certified, a movable device to control the insertion of a slip in said register, and means controlled by said movable device to prevent said ticket issuing mechanism being rendered operative by said controlling member while said movable device is in a position to permit the insertion of said slip.
14. In a register having ticket printing and issuing mechanism, and an operating device therefor, said register being adapted to receive a slip to be certified, a movable device to control the insertion of said slip in said register, means for controlling the operation of said mechanism to cause either a single ticket or two tickets to be printed and issued upon each operation of said operating device, a controlling member for actuating said means, and means controlled by said movable device to lock said controlling member against movement while said movable device is in a position to permit a slip to be inserted in said register.
15. In a register having ticket printing and issuing mechanism, and an operating device therefor, said register being adapted to receive a slip to be certified, a movable device to control the insertion of said slip in said register, means for controlling the operation of said mechanism to cause either a single ticket or two tickets to be printed and issued upon each operation of said operating device, a controlling member for actuating said means, and means controlled by said movable device to move said controlling member from its two ticket position to its one ticket position when said movable device is in a position to permit a slip to be inserted in said register.
16. In a register, ticket printing mechanism, a device for operating said mechanism, ticket issuing mechanism, means for operatively connecting said operating device with said ticket issuing mechanism, said means including a part supported normally in an inoperative position, an actuating member to move said part to its operative position, a lever controlled by said operating device to impart operative movement to said actuating member, a manually operable controlling member connected with said actuating member, a locking member, said register being adapted to receive a slip to be certified, a movable device to control the insertion of a slip in said register, and means controlled by the movement of said movable device to a position to permit the insertion of said slip to move said actuating member into locking relation with said locking member and out of operative relation with said lever.
17. In a register, ticket printing mechanism, a device for operating said mechanism, ticket issuing mechanism, means for operatively connecting said operating device with said ticket issuing mechanism, said means including a part supported normally in an inoperative position, a cam actuated by said operating device, a lever actuated by said cam to move said part to its operative position when said operating device has completed a predetermined portion of its movement, a manually operable lever to move said part to its operative position independently of said operating device, and a device controlled by said cam actuated lever to lock said manually operable lever against movement after initial movement has been imparted to said cam actuated lever.
18. In a register adapted to receive a slip to be certified, a movable device to control the insertion of said slip in said register, said device being movable to a position to permit the insertion of said slip and then into engagement with the inserted slip, and means controlled by said movable device for supporting the inserted slip against the pressure of said movable device.
19. In a register adapted to receive a slip to be certified, a device to control the insertion of said slip in said register, said device being movable into and out of a position to prevent the insertion of said slip, and means controlled by an inserted slip to limit the movement of said device toward its insertion preventing position.
20. In a register adapted to receive a slip to be certified, a device to control the insertion of said slip in said register, said device being movable into and out of a position to prevent the insertion of said slip, and means controlled jointly by said device and the inserted slip to limit the movement of said device toward its insertion preventing position until the slip has been removed.
21. In a register having a passageway for a slip to be certified, a shutter movable into and out of a position to close said passageway and tending normally to move to closing position, a member to support the inserted slip against the action of said shutter, and means to move said member to supporting position after the slip has been inserted in said passageway.
22. In a register having a passageway for a slip to be certified, a shutter movable into and out of a position to close said passageway and tending normally to move to closing position, a supporting member extending normally into said passageway, means controlled by said shutter for moving said supporting member out of said passageway, and means for moving said member into supporting engagement with a slip which has been inserted in said passageway.
23. In a register having a passageway for a slip to be certified, a shutter movable into and out of a position to close said passageway and tending normally to move to closing position, a supporting member mounted on that side of said passageway opposite said shutter, and biased normally toward said passageway, means for moving said shutter and said supporting member in opposite directions to permit a slip to be inserted in said passageway and then releasing the same for movement into engagement with the respective sides of the inserted slip.
24. In a register having a passageway for a slip to be certified, a shutter mounted above said passageway and movable to a position to close said passageway, a supporting member mounted beneath said passageway, a spring tending to move said member into said passageway, and means for raising said shutter and lowering said supporting member to permit the insertion of a slip in said passageway and then releasing the same for movement into engagement with the inserted slip.
25. In a register having a passageway for a slip to be certified, a shutter movable into and out of a position to close said passageway, a locking member, and means controlled by the movement of said shutter to move said locking member to a position to limit the closing movement of said shutter.
26. In a register having a passageway for a slip to be certified, a shutter movable into and out of a position to close said passageway, a locking member, means controlled by the movement of said shutter to move said locking member to

5 a position to limit the closing movement of said shutter, yieldable means to retract said locking member, and a part connected with said locking member and arranged to engage the inserted slip and hold said locking member against movement by said retracting means until the slip has been removed.

10 27. In a register adapted to receive a slip to be certified, a device movable into and out of a position to prevent the insertion of said slip in said register, printing mechanism including an identifying character, and means controlled by the movement of said movable device to move said character into and out of printing position.

15 28. In a register adapted to receive a slip to be certified, a device movable into and out of a position to prevent the insertion of said slip in said register, printing mechanism including an identifying character, means for actuating said movable device, a shaft connected with said actuating means for rotation thereby, and means controlled by said shaft for moving said character into and out of printing position.

20 29. In a register adapted to receive a slip to be certified, printing mechanism having means for printing a ticket and means for printing a record, said record printing means including an identifying character which is movable into and out of printing position, a device movable into and out of a position to prevent the insertion of said slip in said register, and means controlled by the movement of said movable device to move said character into printing position and to render said ticket printing means inoperative when said device is moved to a position to permit the insertion of said slip.

25 30. In a register adapted to receive a slip to be certified and having means for printing and issuing a ticket, and an operating device, a controlling member to cause said means to print and issue either one ticket or two tickets upon each operation of said operating device, a device movable into and out of a position to prevent the insertion of said slip in said register, and means controlled by said movable device to move said controlling member from its two ticket position to a one ticket position and to render said ticket printing means inoperative when said movable device is moved to a position to permit the insertion of said slip.

30 31. In a register adapted to receive a slip to be certified and having means for printing and issuing a ticket, and an operating device, a controlling member to cause said means to print and issue either one ticket or two tickets upon each operation of said operating device, said record printing means including an identifying character which is movable into and out of printing position, a device movable into and out of a position to prevent the insertion of said slip in said register, and means controlled by said movable device to move said controlling member from its two ticket position to its one ticket position, to render said ticket printing means inoperative and to move said identifying character to printing position when said movable device is moved to a position to permit the insertion of said slip.

35 32. In a register, ticket printing mechanism, means for operating said mechanism, ticket issu-

ing mechanism, means for operating said ticket issuing mechanism including a pinion movable into and out of an operative position, a pivoted support for said pinion, an actuating member to impart pivotal movement to said pinion supporting member, means controlled by the operating means for said printing mechanism to impart operative movement to said actuating member, and a manually operable device to impart operative movement to said actuating member independently of said operating means.

40 33. In a register comprising type wheels, printing mechanism for taking impressions from said type wheels on a ticket strip, feeding means for advancing said strip, a normally inoperative operating device, and means for imparting a limited movement to said operating device, means controlled by said operating device to successively actuate said printing mechanism and said feeding means, said actuating means being timed to cause the printing mechanism to make superposed impressions on said strip before any movement is imparted to said feeding means.

45 34. In a register comprising typewheels, printing mechanism for taking impressions from said type wheels on a ticket strip, feeding means for advancing said strip, and a normally inoperative operating device adapted to make a predetermined movement upon each operation of said register, means actuated by said operating device to impart two printing movements to said printing mechanism upon each complete operation of said operating device, normally inoperative means to connect said operating means with said strip feeding means, and means controlled by said operating device to render said connecting means operative after the second printing movement of said printing mechanism.

50 35. In a register, a mechanism for printing identical data on a ticket strip and on a record strip, means for feeding said ticket strip to and from printing position, an operating device, means actuated by said operating device upon each complete operation thereof to cause said ticket printing mechanism to make two printing operations and to cause said record printing mechanism to make a single printing operation, means actuated by said operating device for operating said feeding mechanism, and means for controlling the operation of said feeding mechanism by said operating device to cause either one ticket or two tickets to be issued on each complete operation of said operating device.

55 36. In a register, printing mechanism having separate platens to print respectively on a ticket strip and on a record strip, an operating device, means actuated by said operating device upon each complete operation thereof to impart two operative movements to said ticket platen and a single operative movement to said record platen, a ticket issuing mechanism, means actuated by said operating device for operating said ticket issuing mechanism, and means for controlling the operation of said ticket issuing mechanism by said operating device to cause either one ticket or two tickets to be issued upon each complete operation of said operating device.
